Patented June 19, 1917.

UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

1,230,421.

Specification of Letters Patent. Patented June 19, 1917.

Application filed June 28, 1915. Serial No. 36,738.

To all whom it may concern:

Be it known that I, ALBEN E. LUNDELL, a citizen of the United States, residing at New York, in the county of Bronx and State of New York, have invented certain new and useful Improvements in Automatic Telephone-Exchange Systems, of which the following is a full, clear, concise, and exact description.

10 This invention relates to automatic telephone exchange systems, and more particularly to circuit arrangements for selector switches utilized in such systems.

15 The object of this invention is to provide a circuit arrangement for insuring the proper and quick operation of the selector switches.

In automatic telephone exchanges there is associated with the selector switch an impulse receiving mechanism, such as a line relay, for repeating to the electromagnetic operating means, such as a stepping magnet, the impulses sent out from the subscriber's or other sending station. There may be 20 further associated with such selector switches a steering mechanism, such as a side switch, for controlling the circuits. In order to prevent the untimely actuation of the stepping magnet, it has been proposed 25 to maintain the same normally disconnected from the controlling contact of the line relay and connect it thereto only after the switch is ready to be set in accordance with the impulses. This has been accomplished 30 to 35 by completing the circuit of the stepping magnet only in an operating, for instance the second, position of the side switch; however, in systems heretofore proposed a sufficient time elapsed during the movement of 40 the side switch wipers from the normal to the operating position to make possible the loss of an impulse or impulses.

According to the main feature of this invention, the steering mechanism or side switch is moved from its normal to its operating position upon the first actuation of the impulse receiving mechanism or line relay. As the actuation of the line relay occurs immediately upon the extension of a 45 calling line to an idle trunk, the possibility of current impulses getting lost is reduced to a minimum.

The drawings represent diagrammatically a telephone exchange system, only so much 50 being shown of the circuit arrangements and

apparatus as is necessary for a clear understanding of this invention.

The mechanical construction and the operation of the selector switches and other apparatus used in the building up of a connection between a calling and a called line are well known to those skilled in the art and, therefore, in the following, a detailed description will be given only of the operation of a selector switch utilized in the establishment of a connection.

The subscriber at substation 1, desiring to establish a connection with substation 2, removes his receiver from the switchhook and causes in the well-known manner a trunk 60 finder or line switch 3 to select an idle trunk leading to a selector switch 4. As soon as the wipers of switch 3 are set on the terminals of an idle trunk, a circuit is closed from grounded battery 5 through the left-hand winding of a line relay 6, wiper 7 of a steering or side-switch associated with selector 4, the loop of the calling substation 2, side-switch wiper 8 and the right-hand winding of relay 6, to ground. Relay 70

6 upon energization closes a circuit from ground through its armature and front contact, side-switch wiper 11, and the winding of a quick acting escapement magnet 12, to grounded battery 13. Upon the energization 75 of the escapement magnet 12, the wipers of the side-switch associated with selector 4 are moved into their second or operating position. The calling subscriber proceeds now 80

to cause the setting of selector switch 4 by operating his calling dial 20 provided at substation 1 for interrupting the line circuit a desired number of times. Upon each interruption of the line circuit, line relay 6 releases its armature and closes a circuit 85 for the primary operating magnet 15, which moves in the well-known manner the brushes of selector switch 4 in a rotary direction. The circuit of magnet 15 may be traced from grounded battery 14, winding 100 of magnet 15, back contact and right-hand armature of a slow-acting relay 16, side-switch wiper 17 and the back contact and armature of relay 6, to ground.

Due to the slowness of relay 16 to pull up 105 during the vibration of the armature of relay 6, relay 16 will not become energized. As soon, however, as the sending out of impulses ceases and the armature of line relay 6 is maintained attracted, a circuit is 110

closed from ground, through the armature and front contact of relay 6, side switch wiper 11, contact 21 (closed as soon as the brushes of selector switch 4 leave their normal position), and the left-hand winding of slow-acting relay 16 to grounded battery 22. Relay 16 becomes energized, disconnects magnet 15 and closes a circuit from grounded battery 13 through the winding of escapement magnet 12, left-hand armature and front contact of relay 16 and front contact and armature of relay 6, to ground. The escapement magnet moves the side-switch wipers into position 3, in which position a circuit is closed from ground, through interrupter 23, side-switch wiper 24 and the winding of a secondary or vertical stepping magnet 25, to grounded battery 14. Under the control of magnet 25, the wipers of the selector switch are stepped in a vertical direction until an idle trunk is reached. When the side-switch wiper 11 is moved out of its second position, relay 16 becomes deenergized and opens the circuit of escapement magnet 12. As soon as test brush 26 of selector switch 4 reaches the terminal of an idle trunk (i.e., one to which ground is connected), a circuit is closed from this ground connection through brush 26 of selector 4, conductor 27, side-switch wiper 30, the back contact and left-hand armature of relay 16, and the winding of escapement magnet 12, to grounded battery 13. As long as wiper 26 travels over terminals of busy trunks, no such ground connection is found for the escapement magnet and therefore this magnet remains deenergized. The magnet 12 upon energization causes the wipers of the side-switch to move into position 4, in which position the calling substation line is extended through the wipers 7 and 8 of the side-switch to another switching mechanism provided between selector 4 and the called substation 2, and under the control of substation 1 the desired connection may be established in the well-known manner.

Upon the severing of the connection a ground is sent from the above mentioned switching mechanism through wiper 26, conductor 27, armature and back contact of magnet 12, (this magnet being deenergized in the fourth position of the side-switch), side-switch wiper 31 and the winding of release magnet 32, to grounded battery 33. Release magnet 32, upon energization, closes a locking circuit for itself from grounded battery 33, through its winding and contact 34, and off-normal contact 35 of selector switch 4 to ground. Under the control of the release magnet 32 the selector switch 4 and the associated side-switch will be restored to normal, the locking circuit of the release magnet being maintained closed at contact 35 until selector switch 4 has been

restored to its normal position. After the side-switch has been restored to normal and the receiver at calling substation 1 has been hung up, a ground is sent through the armature and back contact of relay 6, side-switch wiper 17 and off-normal contact 36 to the trunk finder 3, for causing the release of this switch.

Should the subscriber at substation 1 abandon the call before sending out impulses, he would hang up his receiver and cause thereby the deenergization of relay 6. A circuit would be closed thereupon from ground through the armature and back contact of relay 6, the side-switch wiper 17 (which is now in position 2), and the right-hand winding of slow-acting relay 16, to grounded battery 22. The slow-acting relay 16 by pulling up its armature closes a circuit from grounded battery 33 through the winding of release magnet 32, the back contact and right-hand armature of slow-acting relay 16, the side-switch wiper 17, and the back contact and armature of relay 6, to ground. The release magnet 32 causes the restoration of the employed switching mechanism in the same manner as above described.

If the subscriber at substation 1 abandons the call in position 3 of the side-switch wipers, that is to say, after the operation of magnet 15, the release would be accomplished in the same manner as in the last mentioned case.

What is claimed is:

1. In a telephone exchange system, incoming lines and outgoing lines, a selector switch for extending an incoming line toward an outgoing line, an impulse receiving mechanism associated with said selector switch, a normally disconnected electromagnetic means controllable by said impulse receiving mechanism for operating said selector switch, two magnets, and means for connecting into circuit said electromagnetic means upon the first operation of one of said magnets while the other one of said magnets is in normal condition.

2. In a telephone exchange system, incoming lines and outgoing lines, a selector switch for extending an incoming line toward an outgoing line, a line relay associated with said selector switch, a normally disconnected electromagnetic means controllable by said line relay for operating said selector switch, a quick and a slow acting electromagnetic means for connecting into circuit said electromagnetic means upon the first actuation of said quick acting magnet, while said slow-acting magnet remains in normal condition.

3. In a telephone exchange system, incoming lines and outgoing lines, a selector switch for extending an incoming line toward an outgoing line, a line relay asso-

iated with said selector switch, a normally disconnected electromagnetic means controllable by said line relay for operating said selector switch, a quick and a slow acting 5 electromagnet, means operative upon the first actuation of said line relay for operating said quick acting magnet, and means for connecting into circuit said electromagnetic means upon the first actuation of said quick acting magnet while said slow acting 10 magnet is in normal condition.

In witness whereof, I hereunto subscribe my name this 25th day of June, A. D. 1915.

ALBEN E. LUNDELL.
